UNITED STATES PATENT OFFICE.

WILLIAM CALLAGHAN, VALENTINE CUMMINGS, AND JOHN DUNTERMAN, OF JOLIET, ILLINOIS.

REFLECTOR.

Application filed August 20, 1925. Serial No. 51,482.

This invention relates to reflectors, and more particularly to that type which are employed as headlights for vehicles, although it may be used with equal facility as a signal device or upon fixed objects.

There is employed two reflectors which may be simultaneously or selectively illuminated, and which in either case, will throw a light in such a manner as to cast no glare in the eyes of the ordinary observer.

There is embodied a housing in which a conical reflector is eccentrically mounted, and a second reflector of substantially the form of an elliptical cone, arranged at an angle in the said housing. By this construction, it is possible to throw a beam of light directly forward, and at the same time, to employ the second reflector whereby the roadway will be illuminated.

The device is very simple in construction, and rigid in all of its parts, so that it will find ready application either as a headlight, or for any purpose wherein illuminating means of this character are required.

In the drawings:—

Figure 1 is a front elevation.

Figure 2 is a sectional view.

Referring to the drawings, the numeral 10 indicates a housing which is preferably cylindrical, although it may be of any other desired configuration. The housing 10, as usual, is formed of metal, but, of course, other suitable materials can be employed.

Fitted in the housing 10 and brazed thereto, or otherwise secured, is a reflector 11 of substantially conical shape having the lower portion of its interior surface of non-reflecting material. It is to be observed that the open end of the cone is substantially flush with the front open end of the housing 10, and that the rear wall 12 of the cone is in abutting relation to the rear wall 13 of the housing.

Arranged below the conical reflector 11 is a second reflector 14. This reflector, as shown in Figure 1, is substantially elliptical in transverse cross section, and is tapered so that the entire reflector has the form of an elliptical cone. The open end of this reflector 14 is substantially flush with the open end of the housing 10, and with the open end of the conical reflector 11. It is to be observed that the two reflectors are mounted in tangential relation, and that the reflector 14 has its top side, which is in abut-

ting relation to the reflector 11, arranged parallel thereto, while the lower side of said reflector 14 is extended at a greater angle than said upper side. Thus the reflector 14 is arranged at an angle to the housing for a purpose which will be presently described.

The rear wall 15 of the reflector 14 is arranged to abut the rear wall 13 of the housing 10, as in the case of the reflector 11, and it is to be observed that the two reflectors are thereby very compactly and rigidly arranged within the housing.

Formed in the rear wall 13 of said housing are openings 16, which register respectively with suitable openings 17 in the rear walls of the respective reflectors. These openings are each adapted to receive a suitable lamp mounting, as shown, which may be secured in position either by the usual method, or such mountings may be brazed or clamped, as desired.

It will be seen that the lamp 18 of the conical reflector extends parallel to the axis of the casing, while the lamp 19 of the conical elliptical reflector is arranged at an angle to the axis of the casing, so as to be appropriately positioned within the angularly disposed reflector 14.

Referring to Figure 1, it will be seen that by reason of the angular position of the reflector 14 and the disposition of its lamp therein, that said lamp is only partially visible to the ordinary observer, but while this lamp is substantially concealed, the contour of the reflector permits of the downward propagation of a steady and non-glaring beam, as, for example, to illuminate a roadway.

The said reflectors may have their open ends provided with any suitable lens, although this is not essential, and the openings in the housing will obviously be closed to provide a neat structure and prevent the admission of foreign matter.

It is to be understood that the reflectors may be either simultaneously or selectively illuminated.

For example, the conical reflector may be found desirable for city use, where the streets are usually well illuminated, and the roadway smooth, while the conical elliptical reflector may be employed upon roads of doubtful contour, or vice versa.

It is to be observed that the conical reflector will throw a diffused light which will

be non-glaring to the ordinary observer, while the conical elliptical reflector, by reason of its contour, and position in the housing, will throw a diffused light downwardly 5 upon the roadway. In neither case will there be any glare cast in the eyes of one approaching the head lamp.

The device may be used as a signal lantern, and may have suitable colored lens 10 adapted to be illuminated as desired.

An important feature of the invention is the positioning of the reflectors within the housing. The conical reflector is brazed at its rear wall to the rear wall of the housing, 15 and this is also true of the conical elliptical reflector. The conical elliptical reflector also engages by reason of its shape, the periphery of the open end of the housing at two points, and is brazed or otherwise 20 secured to the housing at these points. The conical reflector which is adapted to rest upon the upper side of the conical elliptical reflector in tangential relation thereto, may be brazed or soldered to the conical elliptical reflector, and at its point of contact 25 with the open end of the housing it is similarly brazed or soldered to said housing. By making the cones or reflectors slightly truncated, their rear ends are adapted to 30 fit flush with the rear wall of the housing, so that a rigid construction is provided, while, at the same time, a simple arrangement may be accomplished by passing the 35 lamp mountings through the registering openings in the rear walls of the respective parts.

As stated, the lights may be simultaneously or selectively employed, but in no case will there be a glare cast in the face of any one coming toward the reflector, since in 40 each case provision is made for diffusing the light, while at the same time, the projected light is efficient for all ordinary purposes of a motor vehicle or similar adaptation.

We claim:—

A device of the character described comprising a housing, reflectors disposed in said housing, one of said reflectors having the form of a truncated cone, a second reflector disposed in said housing and having the 50 form of a truncated cone elliptical in cross section, said second mentioned reflector being arranged in abutting tangential relation to said first mentioned reflector and at an angle to the walls of the housing, said reflectors being secured together and secured at their 55 ends to the adjacent walls of the housing, the end walls of the reflectors being disposed in abutting relation flush with the wall of the housing, registering openings in the end 60 walls of the reflectors and the housing to receive lamp mountings, and lamps carried by said mountings and disposed in said reflectors whereby a beam of light is projected forwardly of the housing and a second beam 65 of light is projected downwardly thereof.

In testimony whereof we have hereunto set our hands.

WILLIAM CALLAGHAN.
